UNITED STATES PATENT OFFICE

HAL FREDERICK FRUTH, OF CHICAGO, ILLINOIS, ASSIGNOR TO WESTERN ELECTRIC COMPANY, INCORPORATED, OF NEW YORK, N. Y., A CORPORATION OF NEW YORK

TRANSMITTER

Application filed September 16, 1926. Serial No. 135,723.

This invention relates to transmitters, and more particularly to a variable resistance apparatus for telephone transmitters.

The primary object of this invention is to provide a simple, compact and effective current varying means for electrical transmitters.

In accordance with the general features the invention contemplates the cooperation of a plurality of electrical conductors of different resistance values and differently affected by a vibration responsive means to produce variations in the combined or effective resistances thereof. One embodiment of the invention 10 contemplates a current varying device which forms a part of a transmitter circuit and comprises a low resistance conductor, such as a block of suitable conducting material fixed within the transmitter housing and a high resistance strip adapted to make contact in varying degrees with the conductor block. The high resistance strip is so connected with the transmitter diaphragm that the vibrations of the diaphragm will be imparted thereto, 20 causing the strip to vary its contact with the low resistance block, short circuiting portions of the strip, and thereby producing variations in the combined or effective resistance of the strip and the block in accordance with the vibrations of the diaphragm. The invention 30 is capable of many other applications and some alternative forms thereof are disclosed in the accompanying drawings.

These and other objects will be more apparent from the following detailed description and the accompanying drawings, wherein

Fig. 1 is a central, vertical, sectional view of a transmitter provided with a current varying device which is representative of one embodiment of the invention;

Fig. 2 is a transverse, vertical, sectional view of the transmitter taken on the line 2-2 of Fig. 1;

Fig. 3 is a central, vertical, sectional view of a current varying device which represents an alternative form of the invention;

Fig. 4 is a similar sectional view of a current varying device wherein the high resistance element serves as the diaphragm, and

Fig. 5 is another form of the invention, disclosing a pair of diaphragms coupled with a current varying device.

Referring now to the drawing wherein like numerals have been employed to designate similar parts through the various figures, it will be observed that the numeral 10 in Fig. 1 is employed generally to indicate a telephone transmitter. This transmitter comprises a mouthpiece 11 which is threaded upon a housing 12. Threaded within the housing 12 is a cylindrical casing or shell 14 which is closed at its inner end, its opposite end being opened and threaded on the marginal surface to receive a clamping ring 15. Interposed between the outer end of the casing 14 and an opposed surface of the clamping ring 15 are a pair of elastic rings 17 which provide a resilient mounting or support for the marginal faces of a current conducting diaphragm 18 of duralumin, aluminum or other suitable material. These rings 17 may be constructed of felt, rubber or other suitable material which will supply the proper resilient support for the diaphragm 18.

A current varying means of the type disclosed in Fig. 1 comprises a semi-cylindrical low resistance block 20 of suitable conducting material such as a block of carbon or the like which is secured within the casing 14 by means of brackets 21-21 (Fig. 2). A high resistance strip 22 of conducting material such as gold foil, tantalum, platinum or other material partially encircles the conductor block 20 and is connected at its ends to the diaphragm 18. The curved portion of the strip 22 lies immediately adjacent the curved surface of the block 20 and it will be understood that any outward movement of the diaphragm 18 will cause the strip 22 to be carried more intimately into contact with the adjacent curved surface of the block. Likewise, any inward movement of the diaphragm 18 will cause the strip to be carried away from contact with the block. A screw 24 which is threaded centrally of the closed end of the casing 14 engages with the medial point of the strip 22 so as to hold the strip in contact at one point and in a fixed relation with the block 20. The screw 24 also provides a ter-

5 minal for the transmitter circuit while the diaphragm 18 which is an electrical conductor supplies the other terminal of the circuit, these terminals being connected with wire leads which pass through an opening 23 in the rear central portion of the housing 12. The terminal of one of the leads may be secured in position by means of the screw 24 and the terminal of the other wire lead may be 10 soldered to the diaphragm 18 or secured in any other suitable manner.

15 From the foregoing it will be clear that upon the outward movement of the diaphragm 18 a certain portion of the high resistance strip 22 will be short circuited by being carried more into contact with the block 20 associated therewith and this short circuiting will effectively vary the combined resistance of the strip and the block and hence vary 20 the amount of current flowing through the transmitter circuit. The amount of short circuiting or resistance variation effected by the movement of the strip 22 will be in accordance with and responsive to the vibrations experienced by the diaphragm 18 entering 25 the mouthpiece 11.

20 Referring to Fig. 3 where an alternate form of the current varying device disclosed in Fig. 1 is shown, it will be observed that a cylindrical casing 25 and a clamping ring 26 similar to the casing 14 and clamping ring 15 shown in Fig. 1, has a diaphragm 28 constructed of duralumin, aluminum or the like and elastic supporting rings 29 clamped 30 therebetween. Extending transversely within the casing 25 are a pair of low resistance conductor blocks 31 which are separated at their medial point by an insulating member 32. One of the surfaces of each of these 35 blocks 31 is slightly tapered and disposed immediately adjacent these tapered surfaces is a flexible high resistance strip 33 of conducting material such as one of the non-corrosive noble metals which is clamped at its extremities between the outer ends of the blocks 31 and the inner surface of the wall of the casing 25. The extremities of the strip 33 are electrically connected with the terminals of wire leads which pass through openings 34 40 provided in the casing 25 by means of solder or in any other suitable manner. Interposed between the medial portions of the strip 33 and the diaphragm 28 is a connecting member 36 and it will be apparent that this connecting member will serve to impart vibrations 45 from the diaphragm 28 to the strip 33.

50 The current varying mechanism, just described, functions very similarly to the mechanism disclosed in connection with Fig. 1. As the high resistance strip 33 is caused to move inwardly and thereby to be carried more intimately into contact with the tapered surface of the blocks 31, the short circuiting of the strip 33 will be effected and the resistance 55 of the transmitter circuit correspondingly

lowered. This variation in the effective resistance of the strip 33 and the blocks 31 will cause a relative variation in the current flow and these changes will be directly responsive to and in accordance with the vibrations of the diaphragm 28. The structures disclosed in Fig. 4 are similar to those disclosed in Fig. 3, the only difference being that in Fig. 4 the diaphragm 28 and the connecting member 36 are not present and the high resistance strip 33 has a double function, serving both as a vibratory diaphragm and also as a positive current conducting element having a high resistance.

55 In Fig. 5 a further modification or alternate form of a current varying device is disclosed. A high resistance strip 37 is secured transversely of a casing 38 and diaphragms 40 are secured in position by clamping rings 41 on opposite sides of the strip 37. The central portion of each of the diaphragms 40 is connected with a flexible T-shaped member 42 which is of lower resistance than the strip 37. One end of each of the members 42 is in contact with opposite sides of the strip 37 and is secured in the wall of the casing 38 and upon the vibration of the diaphragms 40 the members 42 will be carried into more or less intimate contact with the strip 37. The contacting of the members 42 with the strip 37 will result in a resistance variation which will relatively affect the amount of current flow in the circuit and it will be noted that in this instance, the high resistance strip is the stationary element while the low members are 60 movable.

65 The types of current varying devices hereinbefore described may be made very compact and by reason of their compactness a transmitter may be relatively small in size and convenient to handle. By reason of the fact that the movable parts are very light a transmitter of the type disclosed will approach a condition of free, undamped vibration which is necessary for high efficiency and quality.

70 Although the invention has been described in connection with a certain type of telephone transmitter, it should be understood that the current varying means may have many other applications and the invention is limited only by the scope of the appended claims.

75 What is claimed is:

1. In a transmitter, a vibratory diaphragm, a housing, a low resistance conductor block fixed within the housing and provided with an arcuate contact surface, a flexible high resistance conductor strip connected with the diaphragm and secured to the block medially of the arcuate surface, the strip being operable in response to vibrations of the diaphragm to vary its contact with the surface of the block and thereby vary the effective resistances of the elements.

2. In a transmitter, a vibratory diaphragm, a fixed low resistance element provided with

an arcuate contact surface, a support therefor, and a high resistance element of very low mass substantially enclosing the arcuate surface of the low resistance element and having both of its ends fastened to the diaphragm, the high resistance element being operable in response to vibrations of the diaphragm to vary its contact with the low resistance element to effect variations in their effective resistance.

10 3. In a transmitter, a vibratory diaphragm, a stationary low resistance block having an arcuate contact surface, and a high resistance foil of very low mass partially encircling the 15 low resistance block and having its ends fastened to the diaphragm, the foil being secured to the block medially of the arcuate surface and operable in response to vibrations of the diaphragm to vary the effective resistance of the block and the foil.

20 In witness whereof, I hereunto subscribe my name this 3rd day of September, A. D. 1926.

HAL FREDERICK FRUTH.
